UNITED STATES PATENT OFFICE.

JOHN L. DINSMOOR, OF NEW YORK, N. Y.

ARC-LAMP

1,143,108.

Specification of Letters Patent. Patented June 15, 1915.

Application filed October 6, 1911. Serial No. 653,116.

To all whom it may concern:

Be it known that I, JOHN L. DINSMOOR, a citizen of the United States, residing in the city of New York, borough of Manhattan, county and State of New York, have invented a certain new and useful Arc-Lamp, of which the following is a specification.

This invention is an arc lamp of that kind wherein the carbons are positioned in downwardly inclined relation to each other so that the flow of current through the carbons, when the latter are separated at their lower ends, will result in the establishment 15 of an arc between said carbons.

The means for controlling and feeding the carbons in the lamp of the present invention are simple in construction and economical of manufacture for the reasons, 20 mainly, that complicated and expensive parts are dispensed with, such as devices, sometimes termed "slipper devices," for effecting a lateral separation of the carbons when striking the arc, a shunt magnet, dash 25 pot, and one or more springs.

For striking the arc, the carbons are lifted in the direction of their length and for equal distances, such operation of lifting the two carbons taking place simultaneously, 30 as a result of which the converging carbons are moved apart at their points for a sufficient distance to establish the arc gap and thus strike the arc. In my lamp, the carbons are guided for movement in predetermined paths so as to be movable only in the direction of their length, no lateral movement of the carbons relative to each other being required in the operations of striking or restoring the arc. Accordingly, 35 the carbons are movable in two directions, first in an upward direction lengthwise thereof for striking the arc, and, second, in a downward direction, under the influence of gravity and in the direction of 40 their length, so as to compensate for the burning away of the carbon material and to restore the arc.

My improved lamp employs a single series coil or solenoid, the plunger of which carries a member positioned for co-operation 50 with a double clutch, the parts of which clutch control the slip of chains or flexible connections with reference to certain guide

tubes. Said guide tubes are separately pivoted to the lamp-frame, and they are adapted for movement relative to each other when the clutches are actuated by the movement of the plunger. The flexible connections which run through the pivoted tubes are each attached at one end to a carbon carrier, the other end being anchored at a fixed point, but intermediate the ends of the flexible connections the latter run loosely over a pulley on a slidable cross head which is guided in the lamp frame, said cross head serving, mainly, the purposes of a counter-weight in automatically taking up the slack in the flexible connections.

Other features of the invention, and the advantages thereof, will appear in the course of the following description taken in connection with the drawings.

In the accompanying drawings, I have illustrated one practical embodiment of the invention, but the construction shown therein is to be understood as illustrative, only, and not as defining the limits of the invention.

Figure 1 is a side elevation, with parts in section, illustrating a regulating mechanism for flaming arc lamps embodying this invention. Fig. 2 is an elevation looking toward the right in Fig. 1, certain of the parts being omitted. Fig. 3 is an enlarged view, partly in elevation and partly in section, of the regulating mechanism at the top part of the lamp. Fig. 4 is an enlarged view, partly in section and partly in elevation, of the parts at the lower end of the lamp, the carbons being shown in their separated positions. Fig. 5 is a view somewhat similar to Fig. 3 illustrating the parts of the regulating mechanism in positions for separating the carbons to strike the arc when the solenoid plunger is drawn upwardly. Fig. 6 is a cross section on the line 6-6 of Fig. 3. Fig. 7 is a detail sectional view illustrating an automatic switch mechanism by which a compensating or substitutional resistance is included in the line circuit when the lamp is out of service. Fig. 8 is a view in perspective illustrating the carbons, the pivoted tubes and the flexible connections whereby the feed of the carbons is controlled by a clutch mechanism associated with the pivoted tubes. Fig. 9 is

a diagram of the lamp circuit. Fig. 10 is an enlarged sectional view illustrating in detail one of the bent tubular members, the clutch carried thereby, and the flexible carbon-supporting member in the form of a link chain, the latter having running engagement with the bent tubular member and adapted to be made fast therewith by gripping action of the clutch. Fig. 11 is a detail view looking at the parts from the left in Fig. 10.

The lamp frame embodies a top plate or member 5, a bottom plate 6, (sometimes termed an "economizer") two pairs of rods 7, 8 attached rigidly, in any suitable way, to the top plate and the bottom plate, another plate 9 positioned intermediate the top plate and the bottom plate, and guide rods 10 attached to the top plate and the intermediate plate 9. The top plate 5 serves as a support for a hood or casing 11, and to this plate is rigidly secured upstanding arms 12 to which is connected a bail 13 by which the entire lamp structure is suspended.

Secured rigidly to the top plate is a supporting bracket 14, upon which is mounted a series coil 15, said series coil being the only coil employed in the lamp, for the reason that the usual shunt coil is omitted. Within the series coil operates a core or plunger 16, the same passing downwardly through the coil and through an opening 17 provided in the supporting bracket 14. The top plate 5 is provided with a central slot or opening 18 and with other slots or openings 19, said plate having upstanding flanges or lugs 20 at the respective sides of slot or opening 18. The solenoid plunger is provided with an upwardly extending rod 21, the upper part of which is threaded as at 22. Said plunger is provided, also, with a depending rod 23 which passes downwardly through slot 18 in top plate 5, the lower part of said rod 23 being threaded. On this lower threaded part of rod 23 is screwed a cross member 24, the same being shown as a plate, the respective parts of which are bent at an angle to each other, and said ends of the plate being forked or slotted so as to loosely embrace certain guide tubes 25, 26 and clutches 27, 28. Each tube 25, 26 is bent or looped upon itself in the form shown more particularly in Figs. 1, 3 and 5 of the drawings, so as to produce a tube having one arm longer than the other. Said tubes are positioned reversely to each other, the long arms of the tubes passing through the slot 18, whereas the short arms of the tube are positioned for operation within slots 19 of the top plate. Each tube is provided with offstanding lugs or ears 29 which fit between flanges 20 of plate 5, and through said lugs or ears and the flanges passes a pivot pin 30, whereby the tube is pivotally supported upon the top plate for swinging movement in the slots 18, 19 there-

of. The looped part of each tube extends above the top plate and into the space of hood 11, whereas the arms of the tube pass through the slots 18, 19 so as to extend below the slotted upper part of the top plate. The long arm of each tube is provided with a slot 31 and around each tube is secured or clamped a sleeve or band 32. As shown in Figs. 1, 3, 5 and 9, the short arm of each pivoted tube is provided with a stop collar 29^a, the latter being of such diameter that it cannot pass through slot 19 in the top plate. When the tube occupies the idle position shown in Fig. 1, collar 29^a rests upon top plate 5 and thus limits the movement of the tube in one direction. Each clutch 27 or 28 consists of a curved plate which is provided on one edge with serrations or teeth 33. The clutch 27 is pivoted at its lower end to a sleeve 32 by means of a pin 34, whereby said clutch 27 is pivotally attached to tube 25. The other clutch 28 is pivoted by a pin 35 to the sleeve 32 of tube 26 so that said clutch 28 is pivoted to and carried by tube 26, as clearly shown.

The member 24 on the depending rod 23 of the solenoid plunger engages the clutches 27, 28, for the purpose of moving them inwardly toward the slots 31 in tubes 25, 26, and said end portions of member 24 act, also, upon the tubes 25, 26 in a manner to move them on their pivots 30. The movement of the clutches and of the pivoted tubes by member 24 is effected by the upward movement of plunger 16 due to the action of the series coil thereon, but when the plunger and member 24 are lowered, tubes 25, 26 swing on their pivots by the action of gravity, the larger heavy arms of the tubes swinging outwardly and away from each other, and the swinging movement of the tubes being arrested by the contact of collars 29^a with top plate 5, see Figs. 1 and 3. When the clutch actuator 24 is lowered, the clutches 27, 28 swing on their pivots by gravity, said clutches swinging toward each other and said clutches being movable with respect to the slotted parts of the pivoted tubes.

36, 37 are carbon holders, each consisting of a plate having forked end portions 38. Carbon holder 36 is fitted slidably to rods 7 of the lamp frame at one side thereof, whereas carbon holder 37 is fitted slidably to the other rods 8 at the opposite side of the lamp frame, as shown more particularly in Fig. 6, whereby the carbon holders are retained in position by the rods of the lamp frame and they are free to slide upon said rods. Each carbon holder is provided with suitable means for the attachment of the carbon thereto, said carbons being indicated at A, B, and positioned in downwardly converging relation.

39 designates a cross head, the end portions of which are slotted at 40, see Fig. 6.

Said cross head is positioned for movement between top plate 5 and intermediate plate 9 of the lamp frame, and the slotted parts 40 of said cross head are fitted slidably on the guide rods 10, whereby said cross head 39 is retained in position within the lamp frame, and the movement of said cross head is directed by the rods 10. The cross head is provided with two pulleys 41, 42, and beneath these pulleys extend the chains or cables 43, 44 which constitute the operative connections between the carbon holders and the parts of the regulating mechanism. The flexible connection 43 is anchored at a fixed point 45 on the top plate 5 from whence said flexible connection passes downwardly to and beneath one pulley 41 on the sliding cross head 39, thence the flexible connection passes upwardly to and through pivoted tube 26, and thence the flexible connection 43 passes downwardly and is attached to carbon holder 37. The other flexible connection 44 is anchored at a fixed point 46 on the top plate 5, from whence said connection passes downwardly to and beneath pulley 42 upon the sliding cross head, from thence said connection 44 passes upwardly to and through pivoted tube 25, and thence downwardly to the carbon holder 36 to which it is fixedly secured. The sliding cross head 39 and the pulleys 41, 42 thereon are of sufficient weight to lower the cross head with respect to the guide tubes 10, for the purpose of automatically taking up the slack in the flexible chains or cables 43, 44, thus keeping said flexible connections relatively taut. The chains or cables pass through the tubes 25, 26 in such relation to the clutches 27, 28 that the toothed faces of the clutches will engage with the links of the chains in a manner to preclude sliding movement of the chains through the tubes when the clutches are forced through the slotted parts of the tubes by the action of member 24 which is carried by the solenoid plunger.

Bottom plate 6 of the lamp frame is provided with a central slot 47 through which pass the lower ends of carbons A, B. Said bottom plate is shown as having a depending member 48 provided with a recess 49, said recessed member constituting the part ordinarily designated as an economizer. Upon the top of plate 6 is a plate 50 composed of asbestos or other heat-resisting material, said plate 50 being provided with apertures 51 for the passage of the carbons.

The upwardly extending rod 21 of the solenoid plunger passes a suitable distance above the solenoid coil, and on this rod are nuts 52, 53. The rod passes loosely through apertures 54 provided centrally in a series of weights 55, 56, 57. The weights are cup-shaped so as to fit telescopically together, said weights constituting a mechanical re-

sistance when the solenoid plunger moves upwardly to predetermined positions within the coil 15. Each weight rests upon the top of the solenoid, and when the plunger moves upwardly to a certain position, the nut 52 engages with weight 55 so as to lift it. A continued upward movement of the plunger and the weight 55 thereof brings said weight 55 into contact with weight 56 so that the weights 55, 56 will be imposed upon the plunger to act as a resistance to the upward movement thereof, but a still further upward movement of the plunger acts to bring the weight 56 into contact with the weight 57, thus imposing all the weights upon the plunger when the latter is moved to an extreme upward position within the coil, substantially as shown in Fig. 5.

The intermediate plate 9 of the lamp frame supports the blow coils 58, the same being secured rigidly to the under side of said plate at the respective end portions thereof. The blow coils are positioned at the lower part of the lamp and in such relation to the carbons that they will exert a magnetic influence upon the arc, for the purpose of properly directing the arc between the carbons, the action of said blow coils being similar to the blow coils used in other lamps of the flaming arc type.

59 designates a resistance coil which is supported on a spool 60 of porcelain or other material, through which spool passes a metallic rod or conductor 61. One end of this conductor is provided with a clip 62 to which is attached an end portion 59a of the resistance coil 59. The lower end of the rod or conductor 61 is connected to the blow coils 58. The coil 59 constitutes a line resistance, and this coil is embraced by an adjustable band 63, to which is secured a conductor 64 which leads to one of the lamp terminals 65. The upper part of the conductor 61 is provided with a clip 66 to which is connected the lower end of another resistance coil 67, said resistance coil being herein referred to as a substitutional or compensating resistance. The resistance coil 67 is connected at its upper part to conductor 68 which leads to one contact 69 of a pair of spring contacts, the other contact of said pair of spring contacts being indicated at 70. Said contact 70 is connected by a conductor 71 with the series coil 15 or with the incoming lead 72 of the lamp, said lead 72 being connected with the positive lamp terminal 73. The solenoid plunger 16 is provided with an arm 74, and extending upwardly from this arm 74 is a tapering member 75 composed of insulating material, said arm 74 and the member 75 being so positioned relative to the spring contacts 69, 70 that the upward movement of the plunger 16 operates to position the insulated member 75 between the contacts 69, 70, for the purpose of separating them

115
120
125
130

and interrupting the flow of current, through the conductor 71, the two contacts, and the compensating resistance 67 when the current flows through carbons A, B, in the operation of the lamp.

The circuit connections are as follows: From the positive post 73 the conductor 72 leads to the series coil 15; from this coil extends a conductor 74 to the carbon B; the current flows from carbon B into carbon A, thence by a conductor 75 to the blow coils 58 which are in series with the lamp circuit; from one coil 58 the current flows into rod 61 and thence through a part of the resistance coil 59, and from thence the current flows through the band 63 and conductor 64 to the negative binding post 65 of the lamp. When no current is flowing through the carbons of the lamp, the solenoid is deenergized, whereupon the plunger 16 drops to a lowered position and the arm 74 is pulled downwardly so as to withdraw the insulated member 75 from engagement with the spring contacts 69, 70, whereupon the current flows from the positive post 73 through the conductor 72, the conductor 71, contact 70 to contact 69, conductor 68, resistance coil 67, connection 66, rod 61, connection 59^a, a part of the line resistance coil 59, band 63 and conductor 64 to the negative post 65. When the lamp is out of service, the current flows around the series coil 15, and through the compensating resistance coil 67 and a part of the line resistance coil 59 to the negative post. Upon switching the current into the lamp, it divides, part of it flowing through coil 67 but the remainder flows through series coil 15, carbon B to carbon A, the blow coils, line resistance coil 59 and conductor 64 to the negative post. The series coil being energized, plunger 16 is lifted a certain distance, thus elevating clutch actuator 24, the result of which is, first, to move the clutches 27, 28 into fixed engagement with chains or cables 43, 44, respectively, and, second, to so act upon the pivoted tubes 25, 26, as to move the said tubes upon their pivots 30. The chains or cables are thus held against movement within the tubes, and the tubes themselves are shifted in position to draw upwardly on the carbon carriers 36, 37, said tubes having the action of bell cranks on the chains or cables for the purpose of simultaneously lifting the carbon carriers, whereby the two carbons are moved for equal distances and in the direction of their length, the result of which is to separate the carbons at their lower ends and strike the arc without, however, moving the carbons laterally with respect to each other. The plunger is held in a raised position by the energy of the solenoid so that the regulating mechanism operates to keep the carbons separated, but as the carbons burn

away at their lower ends, the strength of the current in the solenoid decreases owing to the increased resistance across the arc, whereupon the plunger is lowered slightly by gravity, thus moving clutch actuator 24 and releasing the clutches 27, 28 sufficiently for the chains to slip through the pivoted tubes. The slipping of the chains through the tubes takes place without appreciably affecting the positions of the pivoted tubes so that the arc continues to burn during the operation of feeding the carbons. The feed of the carbons is effected by my regulating means in such manner that the steadiness of the arc is not perceptibly affected, such operation of feeding the carbons being termed a "sneak" feed.

The telescopic weights adapted to be imposed successively upon the solenoid plunger enables me to dispense with the shunt magnet ordinarily employed. These weights are particularly useful in flaming arc lamps, two lamps being used in series. The weights act to compensate for variations in the arc voltage of each lamp. When the two lamps are burning in series, one lamp has a tendency during the feed of the carbons to establish a higher arc voltage than exists in the other of the two said lamps, as a result of which the plunger of one lamp has a tendency to raise to a position within the solenoid above the limit of its upward normal movement. Under such circumstances, the upward movement of the plunger above the normal lifts the nut 52 into contact with weight 55, thus imposing the weight upon the plunger. Should this weight not be sufficient to arrest the upward travel of the plunger and thus compensate for the higher arc voltage in the lamp, then the other weights 56, 57 are imposed successively upon the solenoid by the upward movement thereof, the extreme upward movement of the plunger lifting all the weights as shown in Fig. 5. The weights act to prevent the plunger from being lifted too high with reference to the coil and the other elements of the regulating mechanism.

When the lamp is in service, the plunger is held in a raised position so that the member 75 is between the contacts 69, 70, thereby breaking the circuit through coil 67 and conductor 71, the member 75 being of such length that it keeps the two contacts from engagement while the lamp is burning. Upon deenergizing the coil, the plunger drops and withdraws the member 75 from the contacts, whereupon the spring of the contacts brings them into engagement and the current flows around the series coil and through the resistance 67 to the negative post.

The pivoted tubes used in the present regulating mechanism serve the purposes of

guides for the flexible connections 43, 44 running from the anchor points 45, 46, through the counterweight or cross head 39, and thence to the carbon carriers; and when 5 the clutches are gripped to the flexible connections by the action of the clutch actuator, due to the upward movement of the solenoid plunger, said pivoted tubes perform the functions, also, of bell-crank levers in lifting 10 the carbon carriers, for the reason that each pivoted tube acts to exert an upward pull upon that length of the chain between the carbon carrier and the clutch. The other length of each chain, between the clutch and 15 the fixed anchor point is engaged by a pulley of the cross head, the weight of the latter being imposed normally upon the two chains or cables 44, 45, for the purpose of taking up the slack, thereby keeping the chains or 20 cables in a taut condition.

My regulator may be used in connection with lamps which are supplied with alternating current or with direct current. The substitutional resistance coil 67 herein described is useful particularly in lamps supplied with direct current but when the lamp is to be used on alternating current, it is preferred to use a "choke" coil of a well known form in lieu of the substitutional resistance 25 coil 67.

The parts of the regulating mechanism are so constructed and arranged that the lamp can be transported, or even inverted, without liability of the chains becoming 30 entangled or any of the parts getting out of order.

From the foregoing description taken in connection with the drawings it will be noted that the bent tubes 25, 26, serve the 40 function, mainly, of directing members for the chains or cables 43, 44, the latter serving the purpose of flexible members to connect the electrode carriers 36, 37, with said tubular directing members. These tubular directing members are pivoted for movement 45 in directions to raise or lower the electrode carriers through the medium of the flexible members, the latter having sliding engagement with the tubular directing members. 50 As stated, the clutches are pivoted on the tubular directing members to partake of the pivotal movement thereof, but said clutches are movable, also, into gripping engagement with the flexible members for the purpose of precluding the flexible members from sliding relative to the directing members and of partaking of the pivotal movement 55 thereof, whereby the clutches and tubular directing members coöperate to raise the electrodes or to lower the same.

Having thus fully described the invention, what I claim as new, and desire to secure by Letters Patent is:—

1. In an arc lamp, the combination with

a plurality of carbon holders limited to 65 movement in inclined paths, a plurality of tubular directing members each pivoted intermediate its ends for movement on a horizontal axis, said tubular members being slotted, a plurality of flexible members each 70 having sliding frictional contact with the tubular member and being attached to one of said carbon holders, a plurality of clutches carried by the tubular members and positioned for operation in the slots thereof 75 so as to have gripping engagement with said flexible members, and current operated means coöoperating with said clutches and with said tubular directing members for actuating said clutches simultaneously and 80 for imparting conjoint movement to the tubular directing members, the clutches and the flexible members.

2. In an arc lamp, the combination with a plurality of carbon holders limited to movement in inclined paths, of a plurality of tubular slotted directing members each pivoted intermediate the ends thereof, a plurality of flexible members each having sliding frictional contact with one of said tubular members and attached to one of said carbon holders, a plurality of clutches each carried by one of the tubular directing members and positioned in the slots of said members for direct gripping engagement with 95 one of said flexible members, said clutches being movable with the tubular directing members and being pivoted for movement independently of said tubular directing members, and a current operated member 100 coöperating directly with said clutches for imparting movement simultaneously to the clutches and for actuating said tubular directing members so as to oscillate the latter subsequently to the gripping engagement of 105 the clutches with said flexible members.

3. Means for regulating the electrodes of an arc lamp embodying flexible members having means for supporting the electrodes, a plurality of tubular directing members 110 through which said flexible members are adapted to slide, said directing members being pivoted for movement in directions to raise or lower said electrodes, means for gripping and releasing said flexible members so that the latter are held fast to the directing members or are free to slide there-through under the weight of the electrodes, and an actuator for the gripping and releasing means and for the tubular directing 115 members.

4. Means for regulating the electrodes of an arc lamp embodying flexible members having means for supporting the electrodes, a plurality of tubular directing members 120 within which the flexible members are free to slide, a plurality of clutches each pivoted to one directing member and positioned for

- gripping engagement with the flexible member therein, and an electrically-operated member movable into contact with said clutches for gripping the latter upon the 5 flexible members, said electrically operated member operating to impart movement simultaneously to the tubular directing members for raising or lowering the electrodes.
5. In an arc lamp, the combination with a 10 plurality of electrode carriers, of a plurality of tubular slotted directing members each pivoted intermediate the ends thereof, a plurality of flexible members attached to said electrode carriers, each flexible member 15 being provided with a loop having sliding frictional contact with one of said tubular directing members, means for taking up slack in said flexible members, a plurality of clutches each carried by one of said tubular 20 directing members and positioned for movement in the slot thereof so as to have gripping engagement with a flexible member, and a current operated actuator positioned for direct contact with said clutches 25 so as to actuate the clutches simultaneously in gripping and releasing the flexible members, said current operated actuator acting to also impart movement simultaneously to the tubular directing members.
- 30 6. In an arc lamp, the combination with a plurality of electrode carriers, of a plurality of curved slotted directing members each pivoted intermediate the ends thereof, flexible members attached to said electrode carriers, said flexible members being positioned in sliding frictional contact with said tubular directing members, means for taking up slack in said flexible members, a plurality of clutches each pivoted to one of said tubular 35 directing members for operation within the slot thereof so as to have gripping engagement with the flexible member slidable therein, said clutches being free to fall by gravity away from the flexible members, 40 and actuating means in slidable relation to said clutches and the directing members for imparting pivotal movement simultaneously to the latter and for simultaneously operating said clutches to grip the flexible members.
- 45 7. In an arc lamp, the combination with electrode carriers, of a plurality of tubular directing members pivoted for movement in directions to raise or lower said carriers, a plurality of flexible members fitted slidably 50 in said tubular directing members, each flexible member being anchored at one end and attached at its other end to one electrode carrier, means for taking up slack in said flexible members, a plurality of clutch devices each pivoted to one tubular directing member and positioned for gripping engagement with one of the flexible members for restraining the latter from sliding move- 55 ment relative to said directing member, and an electrically operated actuator coöperating with said clutch devices and with said tubular directing members.
8. In an arc lamp, the combination with electrode carriers, of a plurality of bent 70 tubular directing members positioned reversely to each other and pivoted separately for movement in directions to raise or lower said carriers, flexible members fitted in said tubular directing members for sliding movement therein, said flexible members being connected to said carriers, clutches each pivoted to one of said directing members for gripping engagement with said flexible member therein, a solenoid, a plunger, and 75 a clutch actuator movable with said plunger and positioned for coöperation with said clutches and with said tubular directing members.
9. In an arc lamp, the combination with 80 electrode carriers slidable in inclined paths, of a plurality of tubular slotted directing members each pivoted intermediate the ends thereof for movement in two directions, a plurality of flexible members each having a 85 loop in sliding frictional contact with one of said directing members, said flexible members being connected with said electrode carriers, separate clutches carried by said directing members and positioned for operation in the slots thereof so as to have direct gripping engagement with said flexible members, each clutch being movable on an 90 axis separate from the axis of movement of the directing member by which the clutch is 95 carried, means for taking up slack in the flexible members, and an electrically operated actuator coöperating both with the directing members and with the clutches, said actuator operating to impart movement simultaneously to the clutches and to impart 100 pivotal movement positively in one direction to said directing members simultaneously, the pivotal movement of said directing members in the other of said directions 105 being due to the gravity of the electrodes.
10. In an arc lamp, the combination with a plurality of electrode carriers, of a plurality of tubular slotted direction members each pivoted intermediate the ends thereof, a plurality of flexible members each having a loop in slidable frictional contact with one direction member, said flexible members being attached to said electrode carriers, a plurality of clutches each positioned in the 110 slots of said direction members to frictionally grip one flexible member between itself and one direction member, means for taking up slack in said flexible members, electrically operated means the movable part of 115 which is free from direct mechanical connection with said direction members, and means actuated by said movable part and co-

operating with the clutches and the direction members for imparting pivotal movement first to the clutches and thereafter imparting pivotal movement to the direction members when striking the arc.

5 In testimony whereof I have signed my

name to this specification in the presence of two subscribing witnesses.

JOHN L. DINSMOOR.
